United States Patent Office

Des. 210,265
Patented Feb. 20, 1968

210,265

BLENDER BASE

Henry A. Dewenter, 1477 Old Mill Road,
San Marino, Calif. 91108

Filed Jan. 20, 1967, Ser. No. 5,493

Term of patent 14 years

(Cl. D89—1)

FIG. 1.

FIG. 3.

FIG. 2.

FIG. 1 is a side elevational view of a blender base of my new design;

FIG. 2 is a front elevational view thereof; and

FIG. 3 is a bottom plan view thereof.

I claim:

The ornamental design for a blender base, as shown.
